Primary Examiner—Robert M. Spear*Assistant Examiner*—George D Kirschbaum(74) *Attorney, Agent, or Firm*—Cislo & Thomas, LLP(57) **CLAIM**

The ornamental design for a dog novelty, as shown and described.

DESCRIPTION

FIG. 1 is a left side elevational view of a dog novelty, with the right side elevational view being a mirror image thereof, in accordance with the present invention.

FIG. 2 is a front view thereof;

FIG. 3 is a rear view thereof;

FIG. 4 is a top view thereof; and,

FIG. 5 is a bottom view thereof.

In the drawings, the broken line showing of ears and tail parts depicts environmental subject matter and form no part of the claim.
